his ATTORNEY

UNITED STATES PATENT OFFICE.

WHOLSTON VANDERBILT STOCKTON, JR., OF ALBANY, NEW YORK, ASSIGNOR TO AMERICAN METER COMPANY, INCORPORATED, OF NEW YORK, N.Y., A CORPORATION OF DELAWARE.

METER.

Application filed January 14, 1926. Serial No. 81,166.

The present invention relates to an improvement in meters, one object thereof being to provide means for preventing effectual tampering with the registering or measuring portions of gas meters and the like and more particularly to prevent the insertion of a wire into the measuring mechanism through either the inlet or the outlet ports of the meter. One embodiment of my invention is illustrated in the drawings accompanying the present specification and in which

Figure 1 is a central longitudinal section of an inlet or outlet pipe connection secured to a wall of a meter,

Figure 2, a view in elevation showing the underside of said pipe connection, and

Figure 3, a section thereof on line 3—3 of Figure 2.

Referring to the drawings, a wall of a meter casing 1 is provided with a port 2 and a solder receiving perforation 6. A pipe connection consisting of a threaded coupling 11 and a hollow extension or housing is soldered to the casing 1 in position to cover port 2 and perforation 6, an excess of solder being permitted to flow through and engage said perforation. The hollow extension comprises a conduit 3 having a rear wall 9 opposite perforation 6, a baffle chamber 4 having an annular peripheral wall surrounding port 2 and a recess 8 opening through said peripheral wall into said chamber 4 and having walls arranged to intercept the end of a tampering wire. A shoulder 10 formed in a rear wall of conduit 3 is se-

cured to the upper wall of casing 1. A baffle 7 of annular or curved contour projects rearwardly from the front wall of the chamber 4 into engagement with the wall of casing 1, being positioned between the port 2 and conduit 3 to present a wire deflecting barrier.

In operation, it is contemplated that when a wire is inserted through the conduit 3, the end will be deflected by the baffle 7 and will then ride along the interior surface of the chamber 4 until it reaches the recess 8 where it is intercepted and thus prevented from curling back and then upwardly into the port 2. The recess 8 also serves as a sump for the accumulation of condensates occurring in the conduit and the chamber 4.

I claim as my invention:

In a meter, the combination of a casing having a port, a pipe connection adapted to be secured to said casing and provided with a baffle chamber for covering said port and having a peripheral wall and a front wall, a conduit opening into said chamber through said peripheral wall, a downwardly curved baffle projecting rearwardly from the front wall of said chamber to the casing between said port and said conduit, said peripheral wall having a recess portion effectively positioned opposite said conduit opening to intercept the end of a tampering wire or the like.

In testimony whereof, I have signed my name to this specification this 4th day of January, 1926.

WHOLSTON VANDERBILT STOCKTON, Jr.
